UNITED STATES PATENT OFFICE.

WILLIAM CAMERON MURRAY, OF CORRY, PENNSYLVANIA.

BEDSTEAD CORNER-FASTENER.

1,116,906.

Specification of Letters Patent.

Patented Nov. 10, 1914.

Application filed May 16, 1914. Serial No. 839,065.

To all whom it may concern:

Be it known that I, WILLIAM C. MURRAY, a citizen of the United States, and a resident of Corry, in the county of Erie and 5 State of Pennsylvania, have invented a new and Improved Bedstead Corner-Fastener, of which the following is a full, clear, and exact description.

This invention relates to bedsteads, and 10 more particularly to corner fasteners connecting the side rails to the posts of the head and foot piece.

The general objects of the invention are to improve and simplify the construction 15 and operation of bedstead joints of the character referred to so as to be reliable and efficient in use, comparatively inexpensive to manufacture, and so designed as to provide a strong and substantial connection be- 20 tween the side bars and corner posts.

A further object of the invention is the provision of an improved bracket having simple and effective means for detachably and reversibly connecting the side bar to 25 the bracket.

With such objects in view, and others which will appear as the description proceeds, the invention comprises various novel features of construction and arrangement of 30 parts which will be set forth with particularity in the following description and claims appended hereto.

In the accompanying drawing, which illustrates one embodiment of the invention, 35 and wherein similar characters of reference indicate corresponding parts in all the views, Figure 1 is a sectional view taken through the corner fastener; Fig. 2 is a side view of the joint with portions in section; Fig. 3 is a vertical section on the line 3—3 40 Fig. 2; Fig. 4 is a side view of the joint showing the side rail reversed; Fig. 5 is a fragmentary perspective view of the outer extremity of the bracket; Fig. 6 is a fragmentary view of a portion of a corner post; Fig. 7 is a perspective view of the stud-carrying element; and Fig. 8 is a back view of 45 the base of the bracket.

Referring to the drawing, A designates a 50 tubular corner post of round or any other cross-section, B is a bedstead side bar, C is the bracket to which the side bar is detachably and reversibly connected, and D the stud-carrying element for connecting the 55 bracket detachably to the post.

As shown in Fig. 6, the post A is pro-

vided with a plurality of openings 1 for receiving the heads 2 and shanks 3 of the studs d rigidly secured to the plate or base 4 of the stud-carrying element D, which element is inserted in the post with the headed studs d extending out of the openings 1 of the post. 60

The bracket C comprises a vertical plate 5 which extends from the center of a base 6 which is approximately semi-circular to fit snugly against the exterior of the post 1. This base has openings 7 large enough to receive the heads 2 of the studs d, and each opening is contracted at its top into a recess 8 or slot 8 to receive the shanks 3 of the studs d. As shown in Fig. 2, the base has sloping surfaces 9 adjacent the sides of the recesses 8, so that a wedging action is produced between the heads of the studs d and post 1 70 by the bracket when it is assembled as in Figs. 2 and 4, and a downward pressure exerted on such bracket, the tighter the pressure the tighter being the wedging grip. To accommodate the heads on the studs the 75 vertical plate 5 of the bracket has openings 10. The plate 5 of the bracket C is adapted to be connected with the side bar B, which in the present instance is shown as of angle-iron, and the vertical web 11 thereof has 80 rectangular slots 12 at each end for receiving a rectangular lug 13 on the plate 5 of the bracket C, and adjacent the outer end of the lug 13 is an opening 14 through which extends a clamping bolt 15 that passes 85 through one end of the opening 12 that receives the lug 13, such bolt having a wing or other nut 16 for clamping the parts together. The opening 14 is non-circular, as is the shank 15^a of the bolt, so that the latter cannot turn as the nut is turned. The top flange 11^a of the side bar is adapted to interlock in a recess 17 provided in the upper edge of the plate 5 of the bracket. A corresponding recess 17^a may be arranged in 90 the lower edge of the plate 5, so that the side bar can be reversed, as shown in Fig. 4, compared with the position shown in Fig. 2. The lug-bearing portion or extremity 5^a of the plate 5 is in the form of a rectangular 95 tongue whereby its upper or lower edge will snugly fit the horizontal flange 11^a of the side bar B, as clearly shown in Figs. 2 and 4. On the bracket is an angle piece 18 to which a cross bar extending from one corner 100 post to the other may be fastened. From the construction shown it will be observed 105

110

that none of the parts are riveted together, but that all are detachable, and nevertheless, the parts can be easily and quickly connected together and a strong and substantial corner fastener is provided.

- By reference to Fig. 3, it will be seen that the shanks 3 of the studs *d* taper upwardly so that they wedge in the slots 8 of the openings 7. Thus there are two wedging actions exerted on the bracket C, by the weight sustained thereby, so that the longer the bed is in use, the tighter and more rigid becomes the corner fastener. One wedging action takes place between the heads 2 of the studs *d* and the corner posts A due to the slant of the surfaces 9, and the second wedging action takes place between the tapering shanks 3 and the slots 8 in the bracket C.
- From the foregoing description taken in connection with the accompanying drawing, the advantages of the construction and method of operation will be readily understood by those skilled in the art to which the invention appertains, and while I have described the device which I now consider to be the best embodiment thereof, I desire to have it understood that the device shown is merely illustrative, and that such changes may be made when desired as are within the scope of the appended claims.

Having thus described my invention, I claim as new and desire to secure by Letters Patent:

1. The combination of a tubular post having an opening, a plate in the post, a headed stud rigid on the plate and extending out of the opening, a bracket formed with a base provided with an opening to receive the head of the stud, a key stud extending from the bracket, a side bar having a slot to receive the key stud, and means for fastening the side bar and bracket together.
2. In a corner fastener, the combination of a post, headed studs extending out of the posts from the interior thereof, a bracket comprising a plate and a base, said base having means for engaging the said headed studs, a lug extending from the side of the plate, a side bar having an opening to receive the lug, and a bolt passing through the plate and side bar for securing the same together.
3. In a corner fastener, the combination of a post of circular cross-section, headed studs extending out of the post, a bracket having a base portion of circular cross-section to fit the post and provided with a cen-

trally disposed vertical plate, said base having centrally disposed stud-receiving openings contracted upwardly, said plate having openings contiguous with the openings of the base to accommodate the heads of the stud whereby the base will be wedged between the heads of the stud and the post, and means for securing a side bar to the bracket.

4. In a corner fastener, the combination of a post, a bracket fastened thereto and having a laterally extending lug and provided with an opening at one end of the lug, a side bar having an opening to register with the opening in the bracket and to receive the said lug, and a bolt passing through the openings of the bracket and side bar for securing the latter to the bracket.

5. In a corner fastener, the combination of a post, a bracket fastened thereto and having a laterally extending lug and provided with an opening at one end of the lug, a side bar having an opening to register with the opening in the bracket and to receive the said lug, and a bolt passing through the openings of the bracket and side bar for securing the latter to the bracket, said bracket having a recess into which a portion of the side bar interlocks.

6. In a corner fastener, the combination of a corner post, a bracket fastened thereto and embodying a vertical plate, a side bar of angular cross-section, and means for fastening the vertical flange of the side bar to the plate of the bracket, said plate of the bracket having recesses in its upper and lower edges, whereby the side bar can be reversibly connected with the bracket and have its horizontal flange engaged in either recess.

7. In a corner fastener, the combination of a bracket having a rectangular lug projecting from one side and also having an opening adjacent to one end of the lug, a side bar having an opening large enough to receive the said lug and to register with the opening of the bracket, said lug having its outer face flush with one side of the side bar, and a bolt passing through the opening of the bracket and side bar for clamping the parts together.

In testimony whereof I have signed my name to this specification in the presence of two subscribing witnesses.

WILLIAM CAMERON MURRAY.
